UNITED STATES PATENT OFFICE.

AUGUST M. H. DE BRUYCKER, OF NEW YORK, N. Y.

VENTILATOR.

No. 893,978.

Specification of Letters Patent.

Patented July 21, 1908.

Application filed February 15, 1908. Serial No. 416,056.

To all whom it may concern:

Be it known that I, AUGUST M. H. DE BRUYCKER, a citizen of the United States, and a resident of the city of New York, borough of Brooklyn, in the county of Kings and State of New York, have invented a new and Improved Ventilator, of which the following is a full, clear, and exact description.

The object of the invention is to provide a new and improved ventilator, more especially designed for use on chimneys, and arranged to insure a proper draft at all times by causing a suction in the chimney, irrespective of the wind blowing up or down in the ventilator.

The invention consists of novel features and parts and combinations of the same, which will be more fully described hereinafter and then pointed out in the claims.

20 A practical embodiment of the invention is represented in the accompanying drawings forming a part of this specification, in which similar characters of reference indicate corresponding parts in both views.

25 Figure 1 is a sectional side elevation of the improvement; and Fig. 2 is a like view of a modified form of the same.

The chimney pipe A is surrounded at its upper end by a deflector B of inverted frusto-conical shape, the base of the deflector B lying in a horizontal plane passing through the upper end of the chimney pipe A, so that the deflector B forms with the terminal of the pipe A a pocket C. Centrally above the pipe 35 A and its deflector B is arranged a conical cover D, supported with its base a distance above the top of the pipe A and the deflector B, by the use of braces E attached to the upper end of the chimney pipe A. By reference to the drawings, it will be seen that the base of the conical cover D is approximately the same size as that of the base or upper end of the deflector B, and hence an annular passage is formed between the base of the 40 cover D and the upper ends of the chimney pipe A and the deflector B, for the escape of the smoke and gases rising in the chimney pipe A. The chimney pipe A, the deflector B and the cover D are inclosed in a shell or a

45 mantle F, shown in Fig. 1 as formed of the upper and lower parts F' and F², both of frusto-conical shape and having their bases united approximately opposite the upper end of the deflector B. The apex of the cover D terminates approximately at the top of the upper section F' of the mantle F, and the

base of the cover D is spaced from the wall of the upper section F' a distance corresponding approximately to that of the space between the lower end of the section F² and the chimney pipe A. 60

Now by the arrangement described annular passages are formed between the mantle F, the pipe A, deflector B and cover D, in such a manner that air entering the shell or mantle F either from the top or from the bottom causes a suction in the pipe A, to insure proper draft in the chimney pipe and without danger of the wind, blowing either up or down in the mantle F, from passing into the chimney pipe A. It is understood that the wind blowing downward in the mantle F is deflected by the cover D into the lower section F² of the mantle, and any portion of the wind that may accidentally reach over into the space between the cover D and the deflector B is caught in the pocket C and hence does not pass into the chimney pipe A. Wind entering the lower end of the shell F and blowing in an upward direction is deflected 65 by the deflector B into the space between the upper shell section F' and the cover D, to finally pass out through the upper end of the section F'. The upper shell section F' is preferably connected by braces G with the cover D, and stays G' connect the lower shell section F² with the chimney pipe A. A conical hood H is supported above the shell F by the use of suitable braces I attached to the upper shell section F', and this hood H has its base 70 spaced from the top of the section F', and the diameter of the base is in excess of that of the upper end of the section F'. 75

In the modified form illustrated in Fig. 2 the chimney pipe A', the deflector B', the pocket C', the cover D' and the braces E' are the same as above described in reference to Fig. 1, and the shell or mantle J is provided with the sections J' and J² of frusto-conical shape, united at their bases, located approximately opposite the middle portion of the passage or space between the base of the cover D' and the upper end of the deflector B'. The shell sections J' and J² terminate in cylindrical portions J³, J⁴, of which the portion J³ supports a hood H' by suitable braces I', and the portion J⁴ is connected by stays G² with the chimney pipe A'. In this case the action is approximately the same as the one described above in reference to Fig. 1, 80 that is, wind entering the shell J at the top and moving downwardly is not liable to pass

into the chimney pipe A', nor is the wind entering the shell from below and moving in an upward direction liable to pass into the chimney pipe A'.

5 The ventilator is very simple and durable in construction, and is especially very serviceable for use on chimneys having their terminals adjacent to or near a wall, so that wind is liable to enter the shell or mantle F

10 either at the top or from the bottom. It is understood that in either case a proper draft is maintained in the chimney pipe and without danger of the wind entering the chimney pipe and blowing down the same.

15 Having thus described my invention, I claim as new and desire to secure by Letters Patent:

20 1. A ventilator, comprising a central pipe, a deflector surrounding the said pipe at its upper end and forming a pocket with the same, a conical cover arranged above the said pipe and its pocket, a shell inclosing the said pipe, deflector and cover, the shell having two frusto-conical parts united at their 25 bases, and having their sides spaced from the said cover and the said deflector to form annular passages for the wind and smoke, the apex of the said cover terminating approximately in line with the top edge of the upper part of said shell, and an outer hood of conical shape arranged above the upper shell part.

25 2. A ventilator, comprising a central pipe for the passage of the smoke and gases, a deflector attached to the upper end of the said pipe and of inverted frusto-conical shape, the base of the deflector being flush with the upper end of the said pipe, a conical cover centrally suspended above the said pipe and its deflector, the base of the cover being ap-

30 proximately of the size of the base of the deflector, a shell surrounding the said pipe, deflector and cover, the shell being formed of two frusto-conical parts united at their bases, the latter lying in a horizontal plane con-

45 taining the upper ends of the said deflector and pipe, the apex of the said cover terminating approximately at the top of the upper section of said shell, and a conical hood supported above the top of the shell, the base of the hood being spaced from the top of the 50 upper section of the shell and the diameter of said base being in excess of the top inlet of the shell.

55 3. A ventilator comprising a central pipe, a deflector surrounding the said pipe at its upper end and forming a pocket with the same, a conical cover arranged above the said pipe and its pocket, a shell inclosing the said pipe, deflector, and cover and spaced therefrom, the said shell being open at both 60 ends, the apex of the said cover terminating in line with the upper edge of said shell, and a hood of conical shape supported above the top of the shell.

65 4. A ventilator comprising a central pipe, a deflector surrounding the said pipe at its upper end, a conical cover arranged above the said pipe and deflector, a shell open at both ends and inclosing the said pipe, deflector and cover, the shell having two frusto- 70 conical parts united at their bases and having their sides spaced from the said cover and the said deflector, the apex of the said cover terminating in line with the upper edge of the upper part of the shell, a hood of conical 75 shape above the upper shell part and connected by braces thereto, braces connecting the lower shell part with said central pipe, and braces connecting the said conical cover with the upper part of said central pipe. 80

In testimony whereof I have signed my name to this specification in the presence of two subscribing witnesses.

AUGUST M. H. DE BRUYCKER.
